UNITED STATES PATENT OFFICE.

CHARLES DOUGHTY, OF DENVER, COLORADO, ASSIGNOR OF ONE-HALF TO F. J. HOMAN,
OF DENVER, COLORADO.

LUGGAGE-CARRIER FOR AUTOMOBILES.

1,312,524.

Specification of Letters Patent. Patented Aug. 12, 1919.

Application filed October 9, 1917. Serial No. 195,505.

To all whom it may concern:

Be it known that I, CHARLES DOUGHTY, a citizen of the United States, residing at the city and county of Denver and State of Colorado, have invented certain new and useful Improvements in Luggage-Carriers for Automobiles; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in luggage carriers more especially adapted for use in connection with automobiles, though it must be understood that it is capable of use in connection with any vehicle whose construction is such that it may be advantageously applied. As it is especially designed, so far as the specific construction illustrated in the drawing is concerned, for use with automobiles, the construction will be described with special reference to this use or employment.

Generally speaking the article is adapted to be applied to the running board or running boards of an automobile, and two of the devices may be employed with any car, that is to say, one on either side. This is perhaps preferable where any considerable load is to be carried, since the machine thus equipped will be better balanced than where the entire load is upon one side.

My improvement consists of a sort of rack or skeleton frame composed of two members which form suitable angles. One of these members occupies a horizontal position or a position parallel with the running board to which it is secured by the employment of bolts or other fastening devices. The other member extends upwardly from the running board and forms in conjunction with the running board and the adjacent side of the automobile, a receptacle for luggage, the upwardly projecting member being vertically adjustable, in order to regulate the capacity of the carrier. Furthermore, the two members are jointed at their intersection or angle, whereby the upwardly projecting member may form any angle with the other member between a right angle and a horizontal or parallel position, since the upwardly projecting member may not only be moved to the horizontal

position or parallel with the other member, but its movement may also be continued and carried underneath the running board and it may be folded closely against the other member when it is not desired to use the same, or it may be entirely detached from the machine when it is not needed, as when the automobile is used in cities and on pleasure trips where no considerable amount of luggage is needed. The invention, however, will be found very valuable by picnickers and people going on hunting and fishing trips, and also in traveling any considerable distance with automobiles as is now frequently done.

Having briefly outlined my improvement, I will proceed to describe the same in detail, reference being made to the accompanying drawing in which is illustrated an embodiment thereof. In this drawing:

Figure 1 is a perspective view of my improved luggage carrier, shown in connection with the running board of an automobile, the latter being partly broken away to facilitate the showing of my improved structure.

Fig. 2 is an end elevation of the structure also shown connected with the running board of a car. This view is shown partly in section, taken on the line 2—2, Fig. 3.

Fig. 3 is a section taken on the line 3—3, Fig. 2 looking downwardly.

Fig. 4 is a horizontal section taken on the line 4—4, Fig. 2, the parts being shown on a larger scale.

Fig. 5 is a fragmentary, detail view illustrating the adjustability of the upright member, whereby the latter may be folded against its companion member underneath the running board. In this view the parts are shown on a considerably larger scale than in the other views.

Fig. 6 is a section taken on the line 6—6, Fig. 5. 100

Fig. 7 shows an automobile with the device applied thereto.

The same reference characters indicate the same parts in all the views.

Let the numeral 5 designate my improved luggage carrier considered in its entirety, and composed of two members 6 and 7, which as shown in the drawing occupy positions forming right angles with each other, the said members, however, being adjustable through the medium of a pivot joint 27, whereby the member 6 may form various

obtuse angles with the member 7 of any degree between the vertical and the horizontal. For instance, if it is desired to increase the capacity of the carrier, the member 6 may swing outwardly to the desired degree, thus giving it an incline as distinguished from a vertical position. The upright member 6 is vertically extensible, whereby its height or upright dimension 10 may be regulated at will. Its two parts may be designated respectively by the numerals 8 and 9, the member 8 consisting of two arms 10 connected by slats 12, the said arms being slidably connected with the parts 9 which 15 consist of arms slotted, as shown at 13, to receive set bolts 14 which pass through these slots and also through slots 15 formed in the arms 10. The bolts 14 have heads 16 on one side and wing nuts 17 on the opposite side. 20 By loosening these nuts the two sets of arms may be moved freely upon each other, either for collapsing or expansion purposes or for increasing or diminishing the capacity of the carrier. The lower extremities 25 of the arms 9 are provided with reinforced inwardly projecting lugs 18 which abut and coöperate with similar lugs 19 formed on the outer extremities of horizontally disposed arms 20, of which the member 7 is 30 composed, said arms being slotted to receive fastening bolts 21 which are passed through the arms and also through perforations formed in the running board 22 of the machine. The lugs 18 and 19 are respectively 35 equipped with ratchet teeth to facilitate the securing of said parts in any desired position of adjustment, the two lugs being perforated to receive a bolt 23 which passes through the registering perforations of the 40 two parts and is secured by a wing nut 24. By loosening this nut at each end of the carrier, it will be understood that the member 6 may be swung outwardly and downwardly to vary its angle with the member 7 45 as may be desired. Furthermore, it may be swung underneath the member 6 when for any reason it is not desired to employ the same. Preparatory to the moving of the member 6 into the position of non-use, the 50 two arms 9 and 10 should be collapsed or adjusted to reduce the member 6 to the least possible height. This may be done by loosening the wing nut 17 and moving the arms 8 and their connecting slats 12, down- 55 wardly toward the running board of the machine. When thus collapsed, the wing nuts are again tightened. The nuts 24 are then loosened to allow the ratchet teeth of the two coöoperating lugs 18 and 19 to become 60 disengaged, after which the member 6 is swung first downwardly and then inwardly and upwardly into engagement with the arms 20 of the member 7.

Attention is called to the fact that the 65 arms 9 and 20 of the two members 6 and 7

are interchangeable which is an important point in the manufacture of the article and also in assembling the structure.

In adjusting the member 6 so that it folds against the member 7 in the manner indicated by broken lines in Fig. 5, provision is made for allowing the member 6 together with the set bolt 23 to move downwardly in order to allow the corner 25 to swing clear of the member 7 when the member 6 is in the position shown by dotted lines in Fig. 5, the two positions of adjustment being respectively indicated by broken and dotted lines in said figure. In order to permit this downward movement of the member 6 and 70 the bolt 23, the lug 19 of the member 7 is vertically slotted, as shown at 26. This is necessary for the reason that the member 7 is stationary with the running board, whereby its vertical adjustment cannot be 75 varied.

From the foregoing description the use and operation of my improved luggage carrier will be readily understood. The only change in the running board in order to 80 attach the carrier thereto, is the formation of openings through which the fastening bolts 21 may be passed. As soon as the nuts are tightened on these bolts the device is connected in operative relation with the 85 machine and its adjustment may be accomplished in the manner heretofore described, either for the purpose of varying its luggage capacity or for the purpose of folding the member 6 underneath the running 90 board and into engagement with the member 7, as heretofore described.

Attention is called to the fact that the carrier structure is laterally adjustable on the running board, whereby its capacity may 95 be further increased.

This is due to the fact that the arms 20 of the member 7, when the device fits closely against the outer edge of the running board, extend inwardly beyond the running board 100 as shown at 28, an additional slot 29 being formed in this extension, the said slot being adapted to receive one of the bolts 21 when the device is moved outwardly to leave a space between the outer edge of the 105 running board and the upright parts 9 of the member 6. This is a feature of considerable importance, since ordinarily there will be articles such as fishing rods and other devices which will be long enough to span 110 the space between the arms 20 of the member 7, and, therefore, may be advantageously placed beyond the outer edge of the running board, even though the space is open 115 between the arms 20. This feature will add 120 considerably to the width of the carrier, and virtually gives the same carrying capacity as if the running board were considerably wider, while at the same time no 125 change is made in the running board or 130

other part of the automobile, which, when the carrier is detached, is absolutely the same as it was before.

Having thus described my invention, what

5 I claim is:

1. A luggage carrier for automobiles, comprising two members, one of which is adapted to be attached to the running board, the said members having coöperating abutting lugs arranged underneath the outer edge of the running board and adjustably connected to vary capacity, and to fold underneath the running board when not in use, the lug of the second member being

vertically adjustable bodily on the first 15 member to permit the folding action.

2. The combination with the running board of an automobile of a luggage carrier comprising two members hingedly connected, one member being attached to the 20 running board and slidably mounted thereon for lateral movement to vary the capacity of the carrier, and locking means on the hinge to maintain the other member at any angle of adjustment to vary the capacity 25 of the carrier.

In testimony whereof I affix my signature.
CHARLES DOUGHTY.
